(57) **CLAIM**

The ornamental design for a bag, as shown and described.

DESCRIPTION

FIG. 1 is a perspective view of a bag, showing my new design;

FIG. 2 is a front elevational view of the bag shown in FIG. 1;

FIG. 3 is a rear elevational view of the bag shown in FIG. 1;

FIG. 4 is a right side elevational view of the bag shown in FIG. 1;

FIG. 5 is a left side elevational view of the bag shown in FIG. 1;

FIG. 6 is a top plan view of the bag shown in FIG. 1; and, FIG. 7 is a bottom plan view of the bag shown in FIG. 1. The broken lines in the drawings show portions of the bag which form no part of the claimed design.

1 Claim, 5 Drawing Sheets
